SEWING MACHINE

Joseph Mann, Philadelphia, Pa., assignor to Lewis Invisible Stitch Machine Company, St. Louis, Mo., a corporation of Maine

Application November 16, 1940, Serial No. 365,908

5 Claims. (Cl. 112—209)

The invention herein disclosed relates to a sewing machine that is provided with a differential feed arrangement with which the machine may be utilized as a plain stitcher or for effecting shirring, and the invention comprehends an attachment with which the ordinary lock-stitch sewing machine may be readily and easily transformed into a machine having a differential feed for its usual purpose more particularly for effecting shirring.

In certain operations in the making of dresses, shirts and other garments, shirring is necessary, for example, where the sleeve is sewn to the cuff, yoke to body, and in dresses where the waist is sewn to the skirt. In these and other like arrangements, one of the pieces of cloth to be sewn together is longer than the other. If the ends of two such pieces of cloth are to be even when the pieces are sewn together, the longer piece must be shirred.

It is an object of this invention to provide a sewing machine, of the kind utilized in the making of dresses, shirts and other garments, with feed mechanism that may be adjusted to effectuate shirring concomitantly with the stitching. Another object of the invention is to provide a differential feed mechanism that may be readily and easily attached to the ordinary sewing machine and effect a shirring action. A further object of the invention is to provide such a differential feed mechanism that may be readily and easily adjusted for varying amounts of shirring. Another object of the invention is to provide a mechanism of this kind with which the operator may render the mechanism effective and ineffective at will while the sewing machine is operating.

The foregoing objects and certain advantages that will hereinafter appear are realized in the machine illustrated in the accompanying drawings which machine forms an example of embodiments of the invention. These drawings include:

Fig. 1 which is a side elevation of a sewing machine including the differential feed mechanism of this invention;

Fig. 2 which is a fragmentary plan of the bed of the machine;

Fig. 3 which is a sectional elevation taken along the irregular line 3—3 of Fig. 2;

Fig. 4 which is a transverse sectional elevation taken along the line 4—4 of Fig. 3;

Fig. 5 which is a fragmentary end elevation;

Fig. 6 which is a sectional plan of the presser foot taken along the line 6—6 of Fig. 5;

Fig. 7 which is a bottom plan of the presser foot taken along the line 7—7 of Fig. 5;

Fig. 8 which is a side elevation of a modified form of presser foot;

Fig. 9 which is a bottom plan of the same;

Fig. 10 which is an end elevation thereof;

Fig. 11 which is a plan of top-stitch work done on the machine;

Fig. 12 which is a section of the same taken along the line 12—12 of Fig. 11; and

Fig. 13 which is an isometric of plain stitch work done on the machine.

The machine illustrated in the drawings is mounted in a frame that includes a bed 1 from adjacent one end of which a standard 2 extends. 10 Formed as a part of the standard 2, there is an arm 3 extending from the standard 2 substantially parallel to the base 1. On the end of this arm 3 there is mounted the needle head 4. Through the arm 3 there extends a main shaft 5. This shaft, in the usual manner, extends through the standard 2 and has mounted thereon the usual hand wheel and pulley 6. From the needle head, the needle bar 7 and a presser foot bar 8 extend towards the base. The needle bar 7 carries the needle 9 and it is reciprocated in the usual manner and by the usual mechanism that is operated from the main shaft of the sewing machine. The presser foot bar 8 is slidably mounted in the needle head and, in the usual manner, is resiliently urged downwardly towards the bed of the machine.

Mounted under the bed of the machine, adjacent the front of the machine relative of the direction of work passing through the machine, and journaled in lugs, such as the lug 10, extending from the base of the machine, there is a feed operating shaft 11. This shaft is common to sewing machines of this type, such as the sewing machine known as the "Singer Class 95-80" and it is oscillated through the usual connections with the main shaft of the sewing machine. Another feed operating shaft 12 is mounted below the bed of the machine at the rear of the machine and journaled in lugs extending from the bed of the machine, such as the lug 13. This shaft is also a usual part of sewing machines of this type and it is oscillated through connecting mechanism with the main shaft of the sewing machine.

From the shaft 12 there extends two radial arms 14 and 15. Between these arms there extends a bracket 16 that is journaled in the arms and has formed thereon a feed bracket 17 that extends under the bed of the machine and transverse to the bed of the machine. The bracket 17 is provided with a bifurcated end piece 18 which receives a block 19 that is pivotally secured to the arm of a bracket 20 secured on the shaft 11. Intermediate the ends of the bracket 17 there is the feed bar 21 forming a part of the bracket. This feed bar is channel shape in cross section and carries the feed dogs as hereinafter described.

It will be observed that upon proper oscillation of the shafts 11 and 12 in the manner well known in the art and common in the sewing machines

of the type referred to the feed bar 21 is given a four motion movement. As observed in Fig. 5, by the conjoint action of the shafts 11 and 12 operating on the bracket 17, the feed bar 21 moves to the left then downwardly, then forwardly to the right in the down position, then upwardly and then rearwardly to the left. On the rearward motion, the feeding action takes place. This action is, of course, related to the needle to effect feeding movement while the needle is out of the work.

On the feed bar 21, there are mounted two sets of feed dogs, the 3-row feed dogs 22, and the 2-row feed dogs 23. For the purpose of distinguishing these feed dogs, the rear set 22 relative to the direction of movement of material through the machine may be termed the main feed dogs and the forward set 23 may be termed the auxiliary feed dogs. The feed dogs 22 are offset from the plane of the feed bar 21 and are formed on a bracket 24 that is secured to the feed bar 21, on the flanges thereof, by machine screws 25 and 26. The feed dogs 23 are also offset to be in line with the needle and are formed on a bracket 27 that is secured on a bar 28 by machine screws 29. The bar 28 is slidably mounted in the feed bar 21, slots 30 being provided in the bar 28 through which the screws 25 and 26 pass. This bar 28 extends rearwardly of the sewing machine and has formed on the rear end thereof a lug 31. It will thus be seen that while the feed dogs 22 are constrained to move with the feed bar 21, the feed dogs 23 may have relative movement with respect to the feed bar 21 in the line of feed of material through the machine. It is through this relative movement, which may be effected by the mechanism hereinafter described, that stirring in various amounts and at the will of the operator may be effected.

The mechanism for effecting a differential feeding action of the feed dogs 22 and 23 is mounted upon a bracket that is secured to the under side of the bed of the machine. This bracket includes an arm 32 secured to the bed of the machine and a depending arm 33 at the end of which there is a rearward extension 34. At the juncture between the depending arm 33 and the rearward extension 34 a machine screw 35 extends through the arm of the bracket and forms a shaft upon which a lever 36 is pivotally mounted. One end of the lever is connected through a link 37 to the lug 31 on the bar 28. The other end of the lever has an arcuate slot 38 formed therein. Within the slot 38 there is a roller 39 that engages the sides of the slot. This roller is mounted upon a shaft 40 that extends between a bifurcated arm of an arcuate link 41, the bifurcated end of the link 41 embracing the slotted end of the lever 36. At the opposite end, the link 41 is pivotally mounted upon an eccentric pivot screw 42 that is secured in and extends from an arm 43 secured on and extending radially of the shaft 12 and forming a continuation of arm 14. A spring 44 normally maintains the roller 39 at the lower end of the slot 38 in the lever 36.

With the roller 39 in the lower end of the slot 38, and the machine set for a particular length stitch, the connection of the link 41 with the lever 36 is equi-distant from the pivotal axis of the lever 36 with the connection of the opposite end of the lever to the link 37. With this relation and with the shaft 12 equi-distant from the pivots 16 and 42, the feed dogs 23 will move ex-

actly the same as the feed dogs 22. The feed dogs 23 are, of course, reciprocated in the line of feed, through the arm 43, the link 41 and the lever 36 but the extent of movement in the feeding direction will be exactly the same as the movement of the feed dog 22 when the roller 39 is at the lower end of the slot 38. By raising the roller 39, i. e. by moving the link 41 about its pivotal connection to the screw 42 to raise the roller 39 in the lever 36, the relation above described is disturbed. When the link 41 is positioned so that the roller 39 is at the top of the slot in the lever 36, the connection between the link 41 and the lever 36 is close to the fulcrum point of the lever 36. In consequence, the same amount of movement of the screw 42 carrying the link 41 will cause a larger movement of the end of the lever 36 that is connected to the link 37 and in consequence a greater movement of the feed dogs 23. The effective part of this greater movement of the feed dogs 23 will be during the movement towards the rear of the machine while the feeding action is taking place.

For the purpose of positioning the link 41 to effectuate a differential movement of the auxiliary feed dogs 23, there is provided a lever 45 that is secured on a shaft 46 journaled in the rearward extension 34 of the bracket 33. The shaft 46 extends through the bracket and on the inner end thereof there is secured an arm 47 that extends radially of the shaft 46. To the end of this arm 47, there is pivotally secured one end of a link 48. The other end of the link 48 is pivotally secured through a pivot screw 49 to the end of the link 41 that carries the roller 39. Through this train of links, movement of the lever 45 effects movement of the link 41 to move the roller 39 in the slot 38 of the lever 36. The end of the lever 45 is provided with an opening 50 by means of which a chain may be attached to the lever and to a foot treadle (not shown) beneath the table upon which the machine is mounted. When the end of the lever is pulled downwardly, the link 41 is moved against the action of the spring 44 to raise the roller 39 in the slot 38. Thus, while the machine is operating, the operator may at any time, by moving the lever 45 effectuate a differential action between the main and auxiliary feed dogs.

There is a manually adjustable arrangement for determining the amount of differential movement that will occur between the feed dogs 22 and 23 when the operator actuates the lever 45. The upper end or edge 51 of the lever 45 is shaped as shown and arranged to engage the end of a pin 52 that is slidably mounted in an arm 53 formed on the bracket 33. The upper end of this pin is in position to engage a helical stop 54 that is secured on a shaft 55 extending through and journaled in the bed of the machine. On the upper end of the shaft 55 there is formed integral with the shaft a finger piece and dial 56. This dial reads against an indicator mark 57 formed in the bed of the machine. By rotating the dial 56, any point on the helix 54 may be brought into line with the end of the pin 52. Engagement of the pin 52 with the helix and engagement of the surface 51 of the lever 45 or the corner formed thereon with the pin determines the amount the link 41 is moved to raise the roller 39 in the slot 38 and thus the extent of the differential feeding movement between the main and auxiliary feed dogs 22 and 23.

Cooperating with the feed dogs 22 and 23, there is a presser foot that is mounted upon the end 75 of the presser foot bar 8. This presser foot in-

cludes the bracket 57 that is secured to the presser foot bar 8 by a machine screw 58. On the end of this bracket what may be termed a main presser foot 59 is pivotally mounted. This presser foot has a flat section 60 which engages the feed dogs 22 or presses the material against the feed dogs during the feeding action of the feed dogs and an up-turned forward portion 61. On the rear end of the flat portion 60, there is an upstanding lug 62. To this lug there is pivotally secured what may be termed an auxiliary presser foot which consists of a lever 63 and a resilient sheet metal presser foot or stripper plate 64. The lever 63 has a slotted end section which receives and which is pivotally secured to the lug 62. The auxiliary presser foot 64 is provided with a bracket 64a secured to the side of the lever 63 adjacent the forward end thereof. The auxiliary presser foot is in advance of the main presser foot and includes the plate 64, slightly wider than the main presser foot, and which has an upturned forward end forming a lead-in for the cloth. The auxiliary presser foot is resiliently urged in a downward direction about its pivotal connection by a spring 64b. When the presser foot bar is lowered, the auxiliary presser foot extends over the set of auxiliary feed dogs 23.

With this machine, set up as above described, there is provided a folder. The particular folder illustrated includes a base 65 consisting of a flat, rigid piece of metal having one corner thereof cut away at 66. Through the base 65 there is a slot 67. The slot 67, when the folder is placed on the machine, overlies two tapped openings in the base 1 of the sewing machine, the line joining the centers of which is parallel to the forward edge of the base. The distance between the tapped openings is less than the length of the slot. Extending through the slot and threaded into these openings there are two machine screws 68. As the slot is longer than the distance between the machine screws, the base may be adjusted towards and away from the needle. The folder is secured to this base and consists of a piece of sheet metal having an extension 69 through which there are a pair of parallel slots 70. Machine screws 71 extending through these slots and threaded into the base 65 secure the folder onto the base. At the end of the extension, there is an upright 72 which extends between the extension 69 and an inclined plate 73. The plate 73 inclines from the end of the upright 72 to the base 1 of the machine and at its lower end it is provided with a tongue extension 74. On one edge of this tongue extension, there is a depending lug 75 which is positioned to engage the edge of the presser foot to prevent the folder from extending under the presser foot. At the end adjacent the needle, the plate 73 has an extension 74' which, when the folder is in position, extends near the auxiliary feed dog 23. The edge of this extension converges for a short distance towards the end edge of the plate 73. Between the extension 74' and the edge of the plate at the upright 72, this edge of the plate is bent under, the resulting curved edge 75' diverging towards the end of the plate connected with the upright. The extreme end 76 of this folded over portion is filled in and appears solid. Extending around the bent-over edge of the plate 73, and spaced therefrom, there is a strip 78. The leg of this strip which extends under the plate is folded upon itself and is secured onto the under side of the plate. The legs of the strip converge in accordance with the convergence of

5 the bent-over edge of the plate 73 and the strip is slightly flared at the operator end.

When the folder is in place and the foot described above is on the machine, as illustrated in the drawings, the operation known as top stitching may be performed on this machine. The effect of top stitching is illustrated in Figs. 11 and 12 of the drawings. In this operation, one piece of cloth 77 has the edge folded under as at 78. The other piece of cloth 79 extends under the folded edge and the needle and needle thread passes through the folded edge of the piece 77 and the piece 79. The needle thus penetrates three layers of cloth. The result is that stitches 80 appear on the piece 77 adjacent the folded edge. When this operation is being performed, the piece of cloth 77 passes under the arm of the machine and the end of the cloth passes around the folded over edge of the plate 73 and between the plate and the strip 76'. This folded over edge passes over the auxiliary presser foot and under the main presser foot. The piece of cloth 79 passes outside of the needle head and the end thereof extends beneath the folded end 76 of the piece 77 and the auxiliary presser foot and directly engages both sets of feed dogs. When material is sewn in this way, the folded over edge of the piece 77 does not pass between the auxiliary presser foot and the auxiliary feed dogs. Thus there is no feeding engagement between the folded end 76 and the auxiliary feed dogs. The under piece 79 is engaged by the auxiliary feed dogs and is placed into engagement therewith by the auxiliary presser foot.

35 In the top stitch operation, above described, when it is desired to effect shirring, the lever 45 is actuated as above described, to effect a differential action between the main and auxiliary feed dogs. When this occurs, the auxiliary feed dogs engaging the end section of the cloth 79 pucker that piece of cloth and carries the puckered cloth to the needle. The end section of the cloth 77 is not puckered and the effect illustrated in Figs. 11 and 12 is attained. In these figures, the piece of cloth 79 is illustrated as having been shirred at 81 and 82. Spaced shirring in this way is attained by actuating the lever 45 while the section represented by the numeral 81 is being shirred releasing the lever and again actuating the lever during the section 81. Continued shirring can be effected as illustrated at 82 by maintaining the lever 51 actuated. The amount of material that will be taken up in the shirring depends, of course, upon the setting of the dial 56, that is, the amount the lever 50 is actuated.

40 For effecting shirring in this way, the rear edge of the auxiliary feed dogs should at the end of the feeding movement, come in line with the needle. This ensures that the shir will be positioned under the needle and sewn into place. The plate 64 of the auxiliary presser foot is resilient and terminates adjacent the needle. The edge of the plate serves to retain the shir in position under the needle to which it is brought by the auxiliary feed dogs.

45 On sewing machines of the kind described, the effect of actuating the stitch adjustment is to rotate the shaft 12 with respect to its actuating mechanism and so vary the effective length of the feeding movement of the feed dogs. When this is done, the lever 43 secured to the shaft 12, and in consequence the pivot screw 42, is shifted accordingly. This disturbs the relation of the parts of the actuating mechanism for the auxiliary feed

dogs. It is for this reason that the pivot screw is an eccentric screw. These feed dogs may be moved, slightly, along the line of feed with respect to the bar 28 by rotating the pivot screw 42. As this is an eccentric pivot, the link 41 and in consequence the lever and the feed dogs 23 are shifted. When a change in the length of stitch is made, the machine is actuated by hand to the position in which the feed dogs are at the end of the feeding stroke. The pivot screw 42 is then rotated so that the feed dogs 23 are moved to a position in which the rear edge thereof is in line with the needle. The machine is now set for the new stitch length.

When it is desired to effect shirring concomitantly with straight or plain stitching, stitching such as illustrated in Fig. 13, the presser foot illustrated in Figs. 8, 9 and 10 is used. This presser foot includes a bracket 83 that is secured to the end of the presser foot bar 3 by the screw 53 extending through the slot 84 in the bracket. To this bracket the presser foot is pivotally secured, the presser foot having an upstanding slotted end section 85 which receives the end of the bracket. In advance of the needle opening 86 through the presser foot, the presser foot has two, parallel inclined, lead-in extensions 87 and 88 joined at one edge by an integral end wall 89. These extensions are substantially wider, in the direction of the end wall 89 than the presser foot. To the under side of the forward extension 88 there is secured a spring steel stripper plate 90 that engages the auxiliary feed dogs.

In plain, straight stitching the two pieces of cloth are laid one upon the other. With the presser foot described above, the edge of one of the pieces of cloth, the top piece passes between the extensions 87 and 88, over the stripper plate 90 and under the main presser foot. The other piece of cloth passes under the stripper plate so that it is engaged by the auxiliary feed dogs. Thus, upon a difference in feeding movement between the main and auxiliary feed dogs, shirring of the under piece will be effected.

From the foregoing description of the machine illustrated in the drawings, it will be seen that by this invention there is provided an auxiliary mechanism that may be applied to the ordinary plain stitch sewing machine. With this mechanism, a differential feed arrangement is provided by which shirring may be effected. The mechanism is such that the amount of shirring may be predetermined and shirring can be effected at the will of the operator. The machine retains all of the characteristics of a plain stitch sewing machine, and with the fold arrangement described above, top stitching and shirring may be effected simultaneously.

It will be obvious that various changes may be made by those skilled in the art in the details of the embodiments of the invention illustrated in the drawings and described in detail above within the principle and scope of the invention as expressed in the appended claims.

I claim:

1. In a sewing machine, the combination comprising stitch-forming mechanism, means for operating the stitch-forming mechanism, feeding mechanism for feeding the material operated upon past the stitch-forming mechanism includ-

ing two sets of relatively movable feed dogs, means for effecting a difference in the feeding movement of the feed dogs including a shiftable member, means for shifting the member, and control means therefore including an adjustable stop and a finger piece mounted on the bed of the machine for positioning the stop.

2. In a sewing machine, the combination comprising stitch-forming mechanism including a needle and a loop taker and feeding mechanism for feeding the material operated upon past the needle including two sets of relatively movable feed dogs, common operating means for actuating the two sets of feed dogs in timed relation with respect to the stitch-forming mechanism, means for effecting a difference in the feeding movement in the direction of the feed of the sets of feed dogs, and means for adjusting one set of said feed dogs in accordance with changes in the feeding stroke of the other set of feed dogs.

3. In a sewing machine, the combination comprising stitch-forming mechanism including a needle and a loop taker and adjustable feeding mechanism for feeding the material operated upon past the needle including two sets of relatively movable feed dogs arranged in line in the direction of feeding movement of the feed dogs, means for actuating the two sets of feed dogs in timed relation with respect to the stitch-forming mechanism, means for effecting a difference in the feeding movement of the sets of feed dogs, and means for adjusting the forward set of feed dogs in accordance with changes in the feeding stroke of the rear set of feed dogs.

4. In a sewing machine, the combination comprising stitch-forming mechanism, two, spaced, parallel shafts, means for oscillating said shafts, a feed bar between and extending transverse to said shafts, a connection between one end of said feed bar and one of said shafts arranged to effect a rise and fall of the feed bar, a connection between the other end of the feed bar and the other shaft arranged to effect longitudinal reciprocation of the feed bar, feed dogs carried by said feed bar for feeding material past the stitch-forming mechanism, an auxiliary feed bar slidably mounted on said first mentioned feed bar and arranged to partake of the rise and fall thereof, feed dogs carried by said auxiliary feed bar, and a drive connection between said auxiliary feed bar and the oscillating shaft for effecting longitudinal reciprocation of the auxiliary feed bar including means for varying the longitudinal reciprocation of said auxiliary feed bar independently of said first mentioned feed bar.

5. In a sewing machine, the combination comprising stitch-forming mechanism, means for operating the stitch-forming mechanism, feeding mechanism for feeding the material operated upon past the stitch-forming mechanism including two sets of relatively movable feed dogs, means for effecting a difference in the feeding movement of the feed dogs, control means for said last mentioned means including a control lever, and means for adjustably limiting the movement of said control lever including an adjustable abutment in the path of said control lever, and a finger piece mounted on the bed of the machine and arranged to control said abutment.

JOSEPH MANN.
